S. E. GUINN.

GAS LIGHTER.

APPLICATION FILED MAR. 2, 1918.

1,280,449.

Patented Oct. 1, 1918.

FIG. 2.

By *John Guinn*
Attorney

UNITED STATES PATENT OFFICE.

SAMUEL E. GUINN, OF BOWLING GREEN, KENTUCKY.

GAS-LIGHTER.

1,280,449.

Specification of Letters Patent.

Patented Oct. 1, 1918.

Application filed March 2, 1918. Serial No. 219,956.

To all whom it may concern:

Be it known that I, SAMUEL E. GUINN, a citizen of the United States of America, residing at Bowling Green, in the county of 5 Warren and State of Kentucky, have invented certain new and useful Improvements in Gas-Lighters, of which the following is a specification.

My invention relates to improvements in 10 gas lighters designed primarily to be attached to the gas supply pipe of gas ranges, and adapted to be held in the hand to ignite a burner.

The invention aims to improve the construction disclosed in my pending application for patent Serial No. 146,440, filed Feb. 3, 1917, in that the features are simplified, and the operation is rendered more convenient.

20 One of the principal objects of the invention is the provision of means arranged to ignite the gas by simply tapping the device on the range or other convenient place.

A further object of the invention is to 25 provide means for simultaneously opening the gas valve at the time the operator, by movement of the hand taps the igniter.

The invention also comprehends improvements in the details of construction and arrangement of parts as hereinafter described 30 and particularly pointed out in the claims.

In the accompanying drawings Figure 1 is a perspective view of the igniter.

Fig. 2 is a longitudinal section of same.

35 1 indicates a handle, through which a pipe 2 passes, the pipe being extended beyond the ends of the handle, and is held in fixed relation by a screw 3, and a finishing nut 4. On the forward end of the pipe 2, is a gas chamber 5, considerably larger in diameter than the diameter of the pipe, and in the open end of the latter where it communicates through an opening 6 with the chamber.

Located adjacent the opening 6 and extending 45 through a threaded sleeve on the gas chamber is a threaded stem 7, the outer end thereof having a head, which affords convenient means for adjusting the stem.

In the sleeve is a coil spring 8, which 50 bears against a sparking element 9, while the stem 7, engages the opposite end, the spring creating the necessary tension to force the sparking element forward.

Fastened to the handle is a resilient member 10, the forward end thereof being bent upwardly, as at 11, and passes through an

opening formed in the wall of the gas chamber, and projects slightly therein. On the rear face of the bent up portion 11, is a friction plate 12, against which the sparking 60 element resiliently bears.

Rotatable on the pipe 1, is a disk 13, formed with slots 14, through which headed pins 15, pass. The disk is formed with an opening 16, which is adapted to register with an opening 17, in the handle, the opening 17, serving as a receptacle for additional sparking elements. By rotating the disk, the opening 16, may be brought into registry with the opening 17, for the insertion or removal of extra sparking elements, and by further movement of the disk the opening 17 can be closed to retain the elements for future use.

Mounted in the handle 1, and extending 75 through the pipe, is a reciprocable valve 19 of any convenient type to control the passage of gas to the burner. The valve normally closes the pipe 2, and on its upper end is a thumb piece 20, located adjacent the inner end of the handle. The valve is retained in closed position by a spring 21. The valve shown is purely illustrative of but one form of valve, for it is evident any suitable valve structure which will serve the purpose can 80 be employed.

In addition to the valve 19, a valve 22, is attached to the free end of a flexible connection 25, or to the manifold of the gas range, to insure of the cutting off of the gas should 90 the spring actuated valve fail to work.

In operation, the attachment is connected to the manifold of a gas range, and the valve 22 is turned on. The operator takes the handle in one hand, with the thumb on the 95 thumb piece of the valve 19, then with a quick downward movement of the device toward the range the forward corner of the resilient member 10 taps the surface of the range, and friction element 12 is forced 100 across the face of the sparking element 9, and generates a spark, at the time the operator moves the device to tap the resilient member, the thumb presses on the thumb piece 20 and opens the valve 19, consequently 105 the spark generated ignites the gas, and the pressure of the latter ejects a flame from the front end of the gas chamber, and burner of the gas stove can be readily lighted. The flame will continue as long as pressure on the 110 valve is retained, and as soon as such pressure is removed the spring 19 automatically

closes the valve and the supply of gas is cut off, and of course the flame is extinguished.

The gas chamber is of such diameter, with reference to the opening in the burner tip, that the air contained in the chamber is to supply sufficient mixture with the gas to ignite same when the spark is generated, hence it is not necessary to provide additional means for the admission of air to the chamber.

In connection with the ignition of the gas when the sparking device is operated, it has been found that when the friction element is injected into the chamber in the path of the flowing gas, the latter is momentarily dissipated, or pocketed between said element and the rear wall of the chamber. At this time the spark is generated, with the result that the "thin" volume of gas in such a large space readily mixes with the atmosphere in the chamber and quickly ignites. I have found this decidedly advantageous and purposely provide the frictional element of such length as to choke the gas when the device is operated.

What I claim is:—

1. A gas lighter comprising a gas pipe, an elongated combustion chamber on one end of the gas pipe and considerably larger in diameter than said pipe, a resilient friction element extending through the wall of the combustion chamber, a resiliently mounted sparking element mounted in the wall of the combustion chamber and in engagement with the friction element, the friction element being so positioned that when it is forced inwardly it will generate a spark and will ex-

tend across the path of the flow of gas from the pipe and dissipate said gas between the element and the rear wall of the chamber, a handle mounted on the pipe in rear and spaced from the combustion chamber, and a flexible pipe connected to the rear end of the pipe to supply gas to the pipe, whereby an operator can move the device within a given range and by tapping the friction element to cause ignition of the gas.

2. A lighter comprising a pipe, a combustion chamber on one end of same, a handle on the pipe, a sparking element in the combustion chamber adapted to be operated by the device against an object, and a valve located on the handle for opening the pipe, said valve being positioned to be engaged by the thumb of the operator, whereby when the sparking device is tapped on an object to create a spark the jar will cause opening of the valve for the passage of gas.

3. A lighter comprising a gas pipe having an elongated enlarged open mouth combustion chamber at one end, a sparking device operable in the chamber and including a resilient member which is normally held projected from the chamber and adapted to be tapped on an object to generate a spark, a handle on the pipe and a valve located on the handle to be engaged by the finger of the hand of the operator holding the handle, whereby to open the pipe to permit gas to flow at or about the time the spark is generated by tapping the resilient member on an object.

In testimony whereof I affix my signature.

SAMUEL E. GUINN.
